CLAIM

The ornamental design for a lobed control wheel, as shown and described.

DESCRIPTION

FIG. 1 is a perspective view of a lobed control wheel; FIG. 2 is a front elevational view of the control wheel shown in FIG. 1, a rear elevation view not being shown as it is a mirror image of the front elevational view;

FIG. 3 is a left side elevational view of the control wheel shown in FIG. 1, a right side elevational view not being shown as it is a mirror image of the left side elevational view;

FIG. 4 is a top plan view of the control wheel shown in FIG. 1; and,

FIG. 5 is a bottom plan view of the control wheel shown in FIG. 1.

The broken lines depict portions of the control wheel that form no part of the claim.

The break lines represent indeterminate length.

1 Claim, 4 Drawing Sheets
